Application October 11, 1938, Serial No. 234,498
In Great Britain October 16, 1937

13 Claims. (Cl. 126—350)

This invention relates to geysers and more particularly to the means for controlling the supply of gas and water thereto.

It is usual to provide geysers with a water tap having a projection or lever which is so arranged that it locks the gas tap and makes it impossible to turn on the gas before the water is passing through the geysers, in order to prevent burning out, the gas tap being fitted with a pilot burner which serves to ignite the gas which passes to the gas ring for heating the water when the gas is turned on.

In accordance with the present invention, the gas and water taps are coupled to one another through the intermediary of a driving connection which enables them to be opened and closed by a single actuating member such as a handle, the said driving connection permitting motion of the water tap relatively to the gas tap, so as to enable cold water to be supplied when required, but preventing independent operation of the gas supply control means in the direction for supplying gas.

In order to enable the gas burner to be re-lit automatically in the event of it being blown out accidentally, a pilot burner is preferably provided which is preferably shielded from draughts and which is maintained alight at least all the time the gas tap is turned on. Since the pilot burner is normally arranged at a distance from the main burner, provision is made for ensuring that the pilot burner receives a constant supply of gas, whether the gas tap of the main burner is turned full on or only partly on. The supply of gas to the pilot burner could be controlled by a separate tap but in order to simplify the arrangement, it is preferable to control the gas supply to the pilot burner by means of a separate conduit in the main gas tap arranged so that the gas supply to the pilot burner is still at its maximum even when the main gas tap is in the closed or nearly closed position. By this means the length of the pilot flame is maintained at its maximum irrespectively of the position of the main gas tap.

A further feature of the invention consists in the provision of automatic closing means for cutting off the gas supply in the event of the burner or, where a pilot burner is fitted, the pilot burner becoming extinguished, such means consisting for instance of a spring or the like arranged to act on the gas tap and tending to maintain it in the closed position, a catch being provided for maintaining the gas tap in the open position, the said catch being under the control

of a thermostat, for example a bimetallic strip heated by the burner flame or the pilot flame. By this means, on the thermostat cooling due to the extinguishing of the burner flame or the pilot flame, the catch is released and the gas tap is removed into the closed position by the automatic closing means.

The invention is illustrated by way of example in the accompanying drawings, in which—

Figure 1 is a side elevation partly in section of one constructional form of the invention; Fig. 2 is a cross section through the plug of the water tap; Figs. 3, 3a and 3b show a detail of the driving connection with the parts in different positions, and Fig. 4 is a side elevation partly in section of a second constructional form. Figs. 4a and 4b show a detail of the driving connection in Fig. 4 with the parts in different positions. Fig. 5 shows a plan view of the thermostat, pilot burner, locking means and ignition device. Fig. 6 is an elevational view of the arrangement shown in Figure 5.

Referring to Figs. 1 to 3, the spindle *e* of the water tap *a* is provided with a coupling member *f* which engages with play a corresponding coupling member *g* on the spindle *h* of the gas tap *i*, the amount of play being sufficient to enable the water to be turned on without actuating the spindle *h* as shown in Figs. 3 and 3a. The opening *c* of the plug of the water tap which registers with the bore *d* in the casing of the tap is flared at both ends, as shown for example in Fig. 2, so as to enable the tap to be turned through an angle which may for instance amount to 90 degrees without reducing the water supply.

The plug of the gas tap *i* is provided with a conduit *j* for the main burner and a conduit *r* for the pilot burner, the latter communicating at each end with a groove *q* formed in the periphery of the plug. The plug of the gas tap may be turned into the closed position by means of a coil spring *n* against the force of which the plug is rotated to open the tap, the said spring being fixed at one end and attached at the other to a coupling disc *m* loosely rotatable on the spindle *h* and provided with one or more dogs or teeth *m'* adapted to engage corresponding dogs or teeth *l* on the plug *i*. Sufficient play is provided between the dogs or teeth on the coupling disc *m* and the plug *i* to enable the latter to turn relatively to the former through a sufficient angle to cut off the gas supply to the main burner and if need be reduce the gas supply to the pilot flame without interfering with the disc *m* when the latter is held in the "open" position by means of

a thermostatically controlled locking member (not shown) which engages a notch o provided in the periphery of the disc m . When the conduit j is out of register with the inlet k the groove q will still establish communication between the inlet p for the pilot burner and the conduit r which conducts the gas to the outlet conduits s for the pilot burner. The length of the groove q at each end of the bore r can be varied as required.

In order to prevent the water tap from being turned into the closed position by the spring n , a spring catch f' may be provided for limiting the rotary motion of the member g so as to arrest it when the tap i is in the fully closed position. The spring catch f' , however, is capable of being forced in turning the water tap off by hand.

The gas and water taps may be operatively connected together by means of a displaceable coupling member connected to one of the taps and engaging driving lugs or equivalent driving means provided on the actuating means for the other tap, the said driving means, in one position of the displaceable coupling member, providing a two-way driving connection and in the other position permitting the water tap to be turned on independently of the gas tap but not the gas tap independently of the water tap.

Referring to the embodiment shown in Fig. 4, the gas and water taps are superposed, the coupling member comprising a finger or the like t suspended from the actuating member e' of the upper tap, which in the construction shown is the water tap, by means of a hinge joint or pivot t' so that its lower end engages between a pair of projections u , u' provided on the actuating member v of the lower tap i which in this case is the gas tap, whereby the one actuating member operates both taps in either direction. The finger t can be rocked inwardly on its pivot t' , for instance against the action of a spring t_2 , so as to lie in the path of the projection u' alone, so as to provide a one-way driving connection permitting the water tap to be turned into the open position independently of the gas tap but preventing the gas tap from being turned independently into the open position. In practice, it is preferable to place the gas tap below the water tap, since a more compact arrangement of the parts is obtained thereby, the gas tap being for instance provided with an arm or lug w which is bolted or screwed to a boss w' on the underside of the water tap. Locating means, for instance in the form of a step on the arm and boss are preferably provided for locating the two taps accurately one below the other in the assembly unit. Since the two taps when assembled one below the other occupy little more space than the water tap alone, a very compact arrangement of the control unit is obtained.

Means may be provided in this case also for closing the gas tap automatically in the event of the flame of the gas burner or of a pilot burner co-operating therewith becoming extinguished, the gas tap being for instance provided with a closing spring n housed within a recess in the underside of the central enlarged portion v' of the actuating member v , one end of the said spring being fixed to the spindle of the gas tap or to the inside of the said recess, which forms a casing for the spring, and the other end being secured to a fixed part of the tap or a fitting secured thereto, a catch controlled by a thermostat being provided for maintaining the gas tap in the open position, the said catch engaging a

recess or projection in or on the said casing part. Preferably, the closing spring acts on a disc m_2 which is loose on the spindle of the gas tap and actuates the tap through driving teeth 5 in a similar manner to the teeth m' in Fig. 1 or, as shown, by means of a pin and slot connection comprising a pin m_3 on the disc m_2 which engages stops l_2 forming the ends of a slot or gap in the periphery of a disc l_1 on the spindle h which is for instance provided with a squared portion which fits into a corresponding square aperture in the disc l_1 .

The coupling discs m_1 and m_2 enable the main burner to be turned down while the catch is in the operative position, the arrangement being such that the gas tap can be turned relatively to the automatic closing means through an angle corresponding to the angular distance between the fully open and fully closed positions of the gas tap, as shown in Figs. 3, 3a, 4a, and 4b, respectively. This avoids the necessity of having to disengage the catch by hand when it is desired to extinguish the burner, while enabling the intensity of the flame to be regulated as desired.

The gas burner may also be provided with automatic igniting means adapted to operate when the gas tap is turned on, for instance frictional igniting means operated by means provided on the casing which houses the closing spring or on some other part of the actuating member of the gas tap. If a frictional igniting device is employed which is operated by a trigger or trip lever, the said trigger or trip lever 30 preferably coacts with a projection or recess y provided on or in the casing of the closing spring, as shown in Fig. 4.

The actuating member for the gas tap may also be provided with a pointer which co-operates 40 with a fixed scale or with a dial or the like indicating the on and off as well as the half-on positions of the tap.

Where a pilot burner is provided, the nipple of the pilot burner may be mounted on a lateral extension i' of the gas tap, particularly when the pilot burner is arranged to give a long flame. This nipple may coact with a fixed mixing tube or with a movable pilot burner which plays on a thermostat which maintains the gas tap in the open position in the manner described in the co-pending patent specification Serial No. 234,497, filed October 11, 1938.

In order to enable the quantity of water to be adjusted to suit the water pressure in the locality 55 in which the appliance is to be used, the actuating member e' and the spindle e are provided with a driving connection which enables the angular position of the member e' with respect to the water tap to be adjusted. As shown in 60 Fig. 4, the spindle of the water tap is provided with a series of axial grooves which are engaged by one or more axial projections or keys provided in the opening of the member e' into which the spindle e is fitted. By this means it is only necessary to remove the screw e^3 , lift the actuating member e' off the spindle e and replace it in a different angular position to suit the timing of the water and gas taps required. Normally the gas tap will not commence to open 65 until the handle v has turned through a comparatively large angle, so that there is no risk of the gas tap being left open in the closed position of the water tap. In order to prevent accidental setting of the member e' into a dangerous position, the number of grooves e^2 is re-

duced to that which will only enable the member *e* to be adjusted into a position within the safe region of angular adjustment.

The bimetallic strip may be in the form of a coil, one end of which is fixed and the other operatively connected to a locking member, e. g. a lever or the like having a tooth which engages one or more teeth provided on the main gas tap as described in the co-pending specification Serial No. 234,497, filed October 11, 1938. By employing a bimetallic strip in the form of a coil, the free end of the coil may be formed as an arm and can be connected up directly to the catch member which retains the gas tap or taps in the open position, thereby simplifying the construction of the device. If the pilot burner is allowed to play continuously on the coil, however, there is the danger that the bimetallic strip will become permanently stretched or damaged. Means are therefore preferably provided for directing the pilot flame away from the coil after the catch has come into action, the pilot burner being mounted so as to swivel under the control of the retaining catch, so as to enable the pilot flame to be directed towards the convolutions of the coil or away therefrom in accordance with the position of the catch.

Referring to the diagrammatic arrangement of the automatic closing and lighting means shown in Fig. 5, 1 is a lever fixed on a spindle 2 and having a tooth 3 which engages the recess *o* provided in the disc *m* in Fig. 1 or in the disc *m*² in Fig. 4; on the spindle 2 is fixed a lever 4 having a forked end 5 which engages the end of an arm 6 forming the end of a coil spring 7 composed of a bi-metallic strip, the other end of which is fixed to a baseplate or other stationary point, the arrangement being such that on the spring 7 being heated by the pilot burner, the spindle 2 is rotated anti-clockwise and moves the tooth 3 into engagement with the recess *o* and on the bi-metallic strip cooling again due to the extinguishing of the pilot flame, the spindle 2 is rotated clockwise, thereby withdrawing the tooth from the recess *o*.

The pilot burner nipple 8 coacts with a mixing tube 9 which is pivoted at 10 so as to be capable of swinging under the action of a spring 11 into such a position as to direct the pilot flame onto the spring 7, an arm 12 fixed on the spindle 2 being adapted to bear against the mixing tube 9 and turn it against the action of the spring 11 so as to deflect the pilot flame away from the spring 7 when the tooth 3 is in engagement with the recess in the member 1. By this means, the danger of the bi-metallic strip being overheated or burnt out is avoided.

The igniting means comprise a knurled friction wheel 13 which is operated by means of an arm 14 driven from the disc 1 by a connecting rod 15, the arrangement being such that the angle of rotation of the friction wheel is greater than that of the disc 1. The friction wheel 13 coacts with a flint 16 housed in a tube 16' open at both ends, the said flint being pressed against the friction wheel by means of a finger on a lever 17 pivoted at 18 and acted on by means of a spring 19 which bears against a fixed abutment 20, the arrangement being such that the lever 17 can be moved clear of the end of the tube 16' to allow of the insertion and removal of the flint. The igniting means may comprise a segment having a roughened surface arranged to co-operate with a flint and operatively connected to the gas tap so as to turn when the gas supply to the

pilot burner is turned on. Instead of a segment, a rod having a roughened surface may be employed, the said rod being arranged so as to reciprocate over a flint, on the gas tap being turned on.

The lighting means for the pilot burner and the automatic closing means for the gas tap or taps may be mounted on the geyser in any suitable manner, for instance on a swinging bracket, so as to enable them to be withdrawn for inspection or for facilitating the cleaning of the parts or the insertion of a new flint.

When the pilot burner is provided with automatic lighting means the arrangement may be such that the gas supply thereto is cut off when the gas tap for the main burner is in the closed position.

If the pilot burner remains alight after the main burner has been turned out, however, it is only necessary, to hold the gas tap in the open position until the catch has come into operation, in cases where the pilot flame has been accidentally extinguished and the thermostat has had an opportunity to cool down. In order to enable the gas supply to the pilot jet to be maintained, an inlet slot may be provided of a sufficient length to enable the gas to pass to the pilot jet in any position of the handle of the gas tap, the gas supply being completely cut off by the automatic closing means when the pilot flame is extinguished. The arrangement may also be such that the gas supply to the pilot flame is completely shut off by hand.

By means of the present invention, the gas and water supplies are controlled by a single actuating member, such as a handle, which may also control the operation of the igniting means for the gas, while enabling the temperature of the water to be varied or cold water to be supplied when required.

It is to be understood that the details for carrying out the invention may be modified without departing from the invention. It is also to be understood that the invention is not limited to water heating devices for supplying hot water to baths.

I claim:

1. In a water heater, the combination of a gas tap, a water tap, an actuating handle connected to one of said taps and coupling means having a positive driving connection for coupling the gas and water taps to one another so as to enable both the gas and water taps to be turned on and off by said actuating handle, said driving connection comprising driving elements arranged to permit motion of the water tap alone into the open position but which prevent the gas tap from being turned into the open position alone, with automatic closing means operatively connected to the gas tap and arranged to urge the gas tap into the closed position, a burner arranged to receive gas through the gas tap, a thermostat device located within the heating zone of said burner and locking means under the control of said thermostat for maintaining the automatic closing means inoperative.

2. In a water heater, the combination of a gas tap, a water tap, an actuating handle connected to one of said taps and coupling means having a positive driving connection for coupling the gas and water taps to one another so as to enable the gas and water taps to be turned on and off by said actuating handle, said driving connection comprising driving elements arranged to permit motion of the water tap alone into the open po-

sition but which prevent the gas tap from being turned into the open position alone, with automatic closing means for the gas tap arranged to urge the gas tap into the closed position, a burner arranged to receive gas through the gas tap, a thermostat device located within the heating zone of said burner, locking means under the control of the thermostat for maintaining the automatic closing means inoperative and a lost motion driving connection between the automatic closing means and the gas tap for enabling the gas tap to be turned independently of the automatic closing means in the direction for shutting off the gas supply.

3. In a water heater, the combination as set forth in claim 1, in which the coupling means for coupling the gas and water taps comprises a lost motion driving connection which enables the water tap to be turned through a predetermined distance before the gas tap is operated, so as to enable cold water to be supplied.

4. In a water heater, the combination of a gas tap, a water tap, an actuating handle connected to one of said taps and coupling means for coupling the gas and water taps to one another so as to enable the gas and water taps to be operated by said actuating handle, said coupling means permitting motion of the water tap alone into the open position but having driving elements for effecting a positive driving connection for turning the gas tap into the closed position during the closing of the water tap, said water tap having a plug with a conduit therein which is flared at both ends, so as to enable said opening to register with the inlet and outlet of the tap while the plug is turned through an angle of 90 degrees without reducing the water supply.

5. In a water heater, the combination of a water tap, a gas tap having a casing with inlet and outlets therein for admitting gas to a main burner and a pilot burner, respectively, an actuating handle, a rotary plug operatively connected to said actuating handle and having a conduit therein for co-operation with the inlet and outlet for the main burner and an independent conduit for co-operation with the inlet and outlet for the pilot burner, said plug being rotatable from an initial open position for supplying gas through said conduits into an intermediate position for shutting off the gas supply to the main burner, said independent conduit for the pilot burner extending circumferentially around the plug for a sufficient distance to establish communication between the inlet and outlet in the casing for the pilot burner when the plug is located in said intermediate position, so as to enable the pilot burner to remain alight all the time the main burner is in operation and after the main burner has been extinguished, said plug being further rotatable into a final closed position for shutting off the gas supply to both the main and pilot burners, an actuating handle connected to one of said taps and coupling means for coupling the gas and water taps to one another so as to enable the gas and water taps to be turned on and off by means of said handle, said coupling means permitting motion of the water tap alone into the open position but having driving elements for effecting a positive driving connection for turning the gas tap into the closed position during the closing of the water tap.

6. In a water heater, the combination as set forth in claim 1, in which the locking means comprises a lever and the thermostat device

5 comprises a coiled bimetallic strip having one end thereof fixed and the other end extended to form an arm which engages one end of said lever, the automatic closing means having a locking element for co-operation with said lever.

7. In a water heater, the combination of a gas tap, a water tap, said taps being arranged in superposed relationship, an actuating member connected to the lower tap and having driving elements thereon, an actuating member comprising a finger pivotally connected to the upper tap so as to depend therefrom with its lower end in co-operative relationship with said driving elements, so as to form coupling means for coupling the gas and water taps to one another, said finger being movable out of operative relationship with one of said driving elements so as to enable the water tap to be turned independently of the gas tap in the direction for supplying water and the other driving element being arranged so as to remain in operative relationship with the finger in all positions of the latter and being so located as to establish a positive driving connection for turning the gas tap into the closed position during the closing of the water tap, with automatic closing means operatively connected to the gas tap and arranged to urge the gas tap into the closed position, a burner arranged to receive gas through the gas tap, a thermostat device located within the heating zone of said burner and locking means under the control of said thermostat for maintaining the automatic closing means inoperative.

8. In a water heater, the combination as set forth in claim 7, with means for securing the gas and water taps to one another comprising a boss on the water tap and an arm on the gas tap with a screw connection for fixing said arm to said boss.

9. In a water heater, the combination as set forth in claim 7, with means for securing the gas and water taps to one another comprising a boss on the water tap and an arm on the gas tap, said boss and arm having steps for locating them in register with the gas and water taps in alinement, and screw connecting means for fixing said arm to said boss.

10. In a water heater, the combination of a water tap, a gas tap, actuating means for said water tap, actuating means for the gas tap, and coupling means for coupling the gas and water taps to one another, said coupling means permitting motion of the water tap alone into the open position but having driving elements for effecting a positive driving connection for turning the gas tap into the closed position during the closing of the water tap, with automatic igniting means operatively connected to the actuating member of the gas tap so as to operate when the gas is turned on.

11. In a water heater, the combination of a water tap, a gas tap, an actuating member for the water tap, an actuating member for the gas tap, and coupling means for coupling the gas and water taps to one another, said coupling means permitting motion of the water tap alone into the open position but having driving elements for effecting a positive driving connection for turning the gas tap into the closed position during the closing of the gas tap, and securing means for connecting the water tap to its actuating member, said securing means comprising an adjustable driving connection for enabling the angular position of the water tap to be adjusted with respect to its actuating member so

as to enable the gas tap to open at any desired open position of the water tap.

12. In a water heater, the combination of a water tap, a gas tap, an actuating member for the water tap, an actuating member for the gas tap, and coupling means for coupling the gas and water taps to one another, said coupling means permitting motion of the water tap alone into the open position but having driving elements for effecting a positive driving connection for turning the gas tap into the closed position during the closing of the gas tap, the water tap and its actuating member having co-operating axial grooves and projections, respectively, for connecting the water tap and its actuating member to one another in different angular positions with respect to one another, so as to enable the gas tap to open at any desired open position of the water tap.

13. In a water heater, the combination of a gas tap, a water tap, said taps being arranged in superposed relationship, an actuating handle connected to one of said taps and having driving elements thereon, an actuating member connected to the other tap and having a finger pivoted thereon and arranged for engagement with said driving elements, so as to enable both taps to be turned on and off by said actuating handle, 5 said finger being capable of turning so as to bring it out of engagement with one of said driving elements to enable the water tap to be turned independently of the gas tap in the direction for admitting water but remaining in permanent engagement with the other driving element so as to prevent independent operation of the gas tap 10 in the direction for admitting gas.

MECHEL RABINOWICZ.
